RIGID AWNING

Herbert J. Tomer, Murrysville, Pa.

Application September 17, 1954, Serial No. 32,330

Term of patent 7 years

(Cl. D21—6)

Fig. 1

Fig. 2

To all whom it may concern:

Be it known that I, Herbert J. Tomer, a citizen of the United States, residing at Murrysville, in the county of Westmoreland and State of Pennsylvania, have invented a new, original, and ornamental Design for a Rigid Awning, of which the following is a specification, reference being had to the accompanying drawing, forming part thereof.

Figure 1 is a perspective view of a rigid awning showing my new design; and

Figure 2 is a top plan view of the same.

I claim:

The ornamental design for a rigid awning, as shown.
